UNITED STATES PATENT OFFICE.

MAURICE R. MECHEM, OF CLARION, IOWA.

GATE LATCH.

Application filed April 18, 1924. Serial No. 707,446.

To all whom it may concern:

Be it known that I, MAURICE R. MECHEM, a citizen of the United States, residing at Clarion, in the county of Wright and State 5 of Iowa, have invented certain new and useful Improvements in a Gate Latch, of which the following is a specification.

This invention relates to new and useful improvements in gate latches and has 10 for its principal object to provide a simple and efficient device wherein a gate is adapted for swinging movement in a horizontal plane, means being associated with the gate for holding the same in a locked position.

15 One of the important objects of the present invention is to provide a gate latch of the above mentioned character, which is of such a construction as to enable the same to be operable from either side of the gate 20 so as to permit the gate to swing in either direction as the case may be.

25 A still further object is to provide a gate latch of the above mentioned character, wherein the gate will automatically be locked against swinging movement when the same is returned to its normal position.

30 A further object is to provide a gate latch of the above mentioned character, which is simple in construction, inexpensive, strong and durable and furthermore adapted for the purposes for which it is designated.

35 Other objects and advantages of this invention will become apparent during the course of the following description.

In the accompanying drawing forming a part of this specification and in which like numerals designate like parts throughout the same:

40 Figure 1 is a side elevation of a gate and the latch associated therewith.

Figure 2 is a sectional view taken approximately on line 2—2 of Figure 1, showing an elevational view of the locking 45 means, and

Figure 3 is a top plan view thereof.

In the drawing wherein for the purpose of illustration is shown the preferred embodiment of my invention, the numerals 1 50 and 2 designate a pair of spaced posts. Disposed between the spaced posts 1 and 2 respectively is the gate designated generally by the numeral 3 and the same may be of any well known construction. The gate 55 3 is hingedly supported at one end to the

post 1 in the manner shown at 4 in the drawing and the opposite end of the gate has extending outwardly therefrom a pair of bolts 5 and 6 respectively, the same being arranged adjacent the upper and lower portions of the gate in the manners clearly illustrated in the drawing.

The locking means adapted to cooperate with the bolts 5 and 6 comprises a pair of supporting plates 7 and 8 respectively which are mounted on the inner face of the post 2 in the manner shown in Figure 1 of the drawing, and this means being provided for securing the supporting plate to the post. As the locking means associated with each 70 bolt is substantially of the same construction, the description of one is thought to suffice for the description of both. Pivotaly supported on each plate at their upper ends are the arms 9 and 10 respectively, the pivotal means therefor being shown at 11 and 12. The arms 9 and 10 converge toward their lower ends and pivotally support on their lower ends the bolt engaging and receiving member 13.

The bolt engaging and receiving member 13 is preferably arcuate in design and the ends thereof are pivotally connected to the lower ends of the arms 9 and 10 in the manner shown at 14 and 15 respectively in 80 the drawing. It is to be understood that the lower ends of the arms 9 and 10 are not in any way connected to the plates on which the same are supported so as to enable the proper operation of the arms and arcuate bolt engaging member in the manner hereinafter to be more fully described. Each of the upper arms 9 and 10 which are mounted on the plates 7 are provided adjacent their lower ends with the ears 16 and 17 respectively, the same being arranged

on the lower faces of the arms and this construction provides a means for supporting the upper ends of the rods 18 and 19 respectively. The opposite ends or lower 95 ends of the rods 18 and 19 are fastened to suitable chains shown at 20 and 21 respectively in the drawing and the opposite ends of the chains are in turn fastened to the upper faces of the intermediate portions of the arms supported on the lower supporting plate 8 in the manner shown at 22 and 23 respectively in the drawing, this construction is more clearly illustrated in Figure 2. As is further illustrated in Figure 110

1, the rods and chains are fastened to the upper and lower arms respectively at a point adjacent the supporting plate so as not to interfere with the outward or swinging movement of the gate 3 and the bolts 5 and 6 carried thereby.

Normally the bolts 5 and 6 are arranged in the arcuate locking members 13 in the manner clearly illustrated in Figure 2 and 10 the gate is prevented from swinging on its hinges 4. In order to open the gate so as to permit the same to swing in a horizontal plane, either of the rods are moved upwardly so as to cause the upward movement of 15 the respective arm to which the same is connected whereby the arcuate members 13 are raised upwardly so that the bolts 5 may be out of engagement therewith so that the gate 3 may be swung to an open position in the 20 direction depending upon which of the rods is actuated. In actuating the rod 18, the arms 9 are raised upwardly simultaneously swinging the arcuate members 13 upwardly on their pivots 15 formed on the lower ends 25 of the arms 10. This will enable the gate to be swung outwardly in the direction away from the arms 10. By actuating the rod 19 and the chain 21 carried thereby, the arms 10 will be raised simultaneously 30 swinging the arcuate member 13 on their pivots 14 so that the gate may be swung to an open position in the direction away from the arms 9.

After the gate has been swung to an open 35 position, the arms 9 and the locking members 13 assume their normal positions and the gate may then be swung to a closed position and held in locked engagement by the locking members 13 automatically. In this 40 operation, the bolts 5 and 6 will strike out the outer faces of the arms depending of course on the direction in which the gate has been swung to an open position and the striking of the arms by the bolts will cause 45 a similar upward movement thereof and the locking members 13 so as to enable the bolts to enter the locking members and upon being positioned thereunder the locking mem-

bers will hold the bolts in locked engagement and against swinging movement.

The simplicity of my device enables the same to be readily and easily placed in position and does not require the use of any complicated members or the like for the purpose of actuating the same. Furthermore, the provision of a device of this character enables the gate to be swung open in either direction and the same may be returned to its normal position and held in a locked position automatically. A device 60 of this character may be manufactured at a very low cost, and will further be strong and durable.

While I have shown the preferred embodiment of my invention, it is to be understood that various changes in the size, shape and arrangement of parts may be resorted to without departing from the spirit of the invention and the scope of the appended 65 claims.

Having thus described my invention, what I claim is:—

1. A gate latch including a supporting plate adapted to be secured to a post, a pair of arms pivotally supported at their upper ends on said plate, said arms converging toward their lower ends, and a substantially arcuate shaped locking member pivotally supported at its respective ends to the lower ends of the arms.

2. In combination, a post, a pair of gate latches associated with the post each including a supporting plate secured to the inner face of the post, a pair of arms pivotally supported at their upper ends on said plate, said arms converging toward their lower ends, a substantially arcuate shaped locking member pivotally supported at its respective ends to the lower ends of the arms and adapted to receive a bolt, and means associated with the arms of the two latches for actuating the arms on the same side of the locking member in unison with each other.

In testimony whereof I affix my signature.
MAURICE R. MECHEM.
